LAMP FIXTURE

Lloyd H. Hornbostel, Jr., 1638 Emerson,
Beloit, Wis. 53511

Filed Aug. 21, 1972, Ser. No. 282,295

Term of patent 14 years

Int. Cl. D26—05

U.S. Cl. D48—4 B

FIG. 1.

FIG. 2.

FIG. 3.

FIG. 4.

FIG. 1 is a front elevational view of a lamp fixture incorporating my new design.

FIG. 2 is a side elevational view as seen from the right of FIG. 1.

FIG. 3 is a top view of the lamp fixture.

FIG. 4 is a fragmentary cross-sectional view taken along the line 4—4 of FIG. 1.

I claim:

The ornamental design for a lamp fixture, as shown.
